UNITED STATES PATENT OFFICE.

WILHELM HAPPEL, OF OPPENHEIM, GERMANY.

METHOD OF MANUFACTURING CLOTHES PEGS OF WIRE.

Application filed October 30, 1926, Serial No. 145,283, and in Germany November 17, 1925.

The method according to the invention makes it possible to make clothes-pegs of wire, the free end of the one U-shaped arm of the wire being bent upward again and forming a handle, same as the free end of the other arm of the wire which projects through the U-arms.

The invention is characterized in that the ends of a straight piece of wire are at first wound to form each one eye said eyes being directed in opposite directions, whereupon arms are formed by bending the wire at right angles at a certain distance from the ends. The front portions of these arms are bent again, that of the one arm at right angles inwardly and that of the other arm at an obtuse angle outwardly. The web between the arms is then wound to several spirals so that the inner ends of the arms come into contact the one with the other, whereupon one of the arms is bent in U-shape over the other arm so that the bead of this other arm projects from between the arms of the U, formed by the first mentioned arm.

The new manufacturing method is illustrated, by way of example, in the accompanying drawing in which

Fig. 1 shows the piece of wire from which a clothes peg has to be made.

Figs. 2, 3, 4, 5, 6, 7 and 8 show each the wire after one of the successive working phases.

The ends of the piece of wire a are bent to form each an eye b^1 , b^2 respectively (Fig. 2) said eyes being turned in opposite directions. In the second phase the wire a is bent at d^1 and d^2 at right angles so that at the one end a straight arm a^1 and at the other end an arm is formed the inner portion a^3 of which is straight, the outer end portion a^4 being bent outward at an obtuse angle (Fig. 3). The front portion of arm a^1 is

bent again at right angles to form an arm a^2 which is parallel to the web a (Fig. 4). In 45 the fourth phase the arm a^2 is bent further towards the web a and slightly out of the plane in which the other parts of the wire are situated (Fig. 5). The fifth working phase consists in winding the web a to form 50 a double spiral A (Fig. 6) so that the points d^1 d^2 at which the arms begin come into contact the one with the other. In the sixth working phase the arms are crossed (Fig. 7) and in the seventh working phase the arm a^1 55 is bent at about half its length in U-shape over the bend d^2 of the other arm (Fig. 8). The arms a^2 , a^4 form then the handles to be compressed for opening the clothes peg.

The bending of the straight wires a is 60 carried out mechanically and continuously by feeding one wire a after the other into the bending mechanism.

I claim:—

A method of manufacturing clothes pegs 65 of wire, comprising rolling the ends of a straight piece of wire into eyes turned in opposite direction, bending said wire at right angles to form two straight arms, in bending the outer end portion of one of said 70 arms outwardly at an obtuse angle, bending the outer end portion of the straight arm to form an arm parallel to the web, bending said parallel arm towards said web and slightly out of the plane in which said web 75 is situated, winding said web to form two spirals so that the bends at which the arms begin touch one another, and bending said straight arm at half its length in U-shape over the bend at which the other arm begins, 80 so that said eyes form the handles of the clothes peg which are to be compressed to open the clothes peg.

In testimony whereof I affix my signature.

WILHELM HAPPEL.
